UNITED STATES PATENT OFFICE.

LUIS B. HOCHSTEIN, OF ENDICOTT, NEW YORK.

GUN-ACTION.

1,325,400.

Specification of Letters Patent. Patented Dec. 16, 1919.

Application filed April 25, 1919. Serial No. 292,607.

To all whom it may concern:

Be it known that I, LUIS B. HOCHSTEIN, a citizen of the United States, and a resident of Endicott, in the county of Broome 5 and State of New York, have invented a new and Improved Gun-Action, of which the following is a full, clear, and exact description.

Among the principal objects which the 10 present invention has in view are: to shorten the lever movement; to augment the magazine capacity; to readily suspend the automatic effect; to simplify the construction; to perfect closure of the breech; to increase 15 the rapidity of discharge of the arm; to facilitate holding sights on target while operating action; to permit the use of long cartridges; to facilitate the loading and re-loading; and to facilitate the repair or re- 20 placement of the parts of the mechanism.

Drawings.

Figure 1 is a longitudinal section of the breech block and stock of a gun, showing 25 the mechanism in the closed or discharged position of the parts;

Fig. 2 is a similar view showing the mechanism in the position assumed thereby at the moment of introducing a loaded car- 30tridge and of ejecting the discharged shell;

Fig. 3 is a similar view showing the positions assumed on the first part of the movement of closing the breech, the breech block being shown as arrested in its loading position 35 with the loaded cartridge in position to be introduced to the barrel of the gun;

Fig. 4 is a side view of a stock constructed and arranged for housing the gun herein disclosed, showing a magazine in 40 position thereon and the feeding spring therefor;

Fig. 5 is a top plan view of the same;

Fig. 6 is a vertical cross section taken as on the line 3—3 in Fig. 1;

Fig. 7 is a similar section taken on the line 4—4 in Fig. 2;

Fig. 8 is a detail view in perspective showing a locking member for arresting the upward movement of the breech block.

Fig. 9 is a fragmentary detail view showing the path of movement of pin 19 and correlated parts.

Fig. 10 is a detail perspective view of one of the magazine gates 54.

Description.

As seen in the drawings, the hand lever

12 is primarily pivoted by the pin 13 on the extractor lever 14. The lever 14 is primarily pivoted in the frame on the pin 60 15. The movement of the short end of the lever 14 between the pins 13, 15, swings the lever 12 and the pin 13 thereof lengthwise of the gun. This movement of the lever is controlled by the cams 16, 17, and the rid- 65 ing pin 18, the ends 19 whereof are shaped in correspondence with the travel of the said pin on the said cams.

Three mechanisms are operatively connected with, for control by, the lever 12. 70 The mechanical arrangement is such as to secure the requisite action of the said mechanism with as little movement of the lever 12 as possible. To this end, the breech block elevator 20, the straight link 21, the 75 toggle links 22 and 23, and the extractor lever 14, are pivotally and co-operatively connected and arranged to shift the pivot movement successively from the pin 13 to the pin 24, and to the pin 15. 80

The various instrumentalities indicated by the ordinals above set forth have for their purpose a series of distinct and relatively successive functions, to wit:

(1) The lowering of the breech block. 85
(2) The withdrawal of the empty shell by the extractor.

(3) The elevating of the breech block to the loading position for the advance of the extractor. 90
(4) The placing of the cartridge in the firing chamber.

(5) The raising of the breech block to the firing position. 95

The first two functions are totally completed when the hand lever 12 is moved away from the pistol grip of the stock to the position shown in Fig. 2 of the drawings, and the remaining three functions are performed during the return of the lever 100 to the position shown in Fig. 1.

Coincident with the performance of the functions indicated, a series of corollary functions are performed, to wit:

(1) The cocking of the hammer. 105
(2) The delivery of a cartridge from the magazine to the breech block.
(3) The extraction and ejection of the empty shell.

(4) The introduction to the extractor of 110 the cartridge.

It will be noted that the movement of the lever 12 from the position shown in Fig. 1 to that shown in Fig. 2, is such as

may be accomplished by expanding the hand without removing the fingers from the grip opening and the trigger opening 25, or the thumb from the pistol grip 26 of 5 the stock 27. During the first part of this movement, the lever 12 pivots on the pin 13. Throughout the first portion of said 10 movement and simultaneously, the hammer 28 is rocked on its pivot 29 and the lever 20 carrying the breech block 30 is carried on its pivots 24 and 31.

The movement of the hammer results from the engagement of the riding pin 18 with the loop 32 at the back of the hammer 28, the pin 18 being rigidly mounted in the extension 33 integrally connected with, and forming a part of, the lever 12. The movement of the lever 20 is the result of the connection by the link 21 of the two levers 12 15 and 20. The link 21 is pivotally connected to the levers 12 and 20 by means of pins 34 and 35, respectively. The pin 24 extends through a slot 36 in one end of the lever 20, the said lever swinging constantly on 25 the pin 31 in the breech block 30. The opposite end of the lever 20 has a roving action accommodated by the elongated slot 36. The coupling by the link 21 of the levers 12 and 20, is such as to magnify the movement of 30 the end of the lever 20 connected with the breech block 30, during which time the lever swings on the pin 24. The result of the multiplied movement is that when the pin 18 reaches the end of the cam 16, and the hammer 35 is partially cocked, the breech block is in its fully lowered position, where it receives a ball-loaded cartridge or shell 37 from one or other of the magazines 50 or 51. During this movement, the lever 20 has been 40 moved relative to the pin 24 until the said pin engages the extremity of the slot 36.

It will be noted that the movement of the lever 12 is continued after the breech block 30 and lever 20, controlling the same, have 45 come to rest, the pin 18 being drawn to a position below the cam 16. During this movement, the extractor 14 is carried from the position shown in Fig. 1 of the drawings to the position shown in Fig. 2.

50 It will be noted that the loop 32 of the hammer 28 swings the pin 18 and extension 33 and lever 12 forward, causing the end connected with the lever 14 to rock on the short end of the lever 14 and the latter on 55 the pivot 15 thereof. Rocking the lever 14 in this manner throws the free end of said lever rapidly back from the position shown in Fig. 1 to the position shown in Fig. 2. The lever 14 is bifurcated, the free ends of 60 said lever resting in slots in the sides of the extractor bar 39. The sides of the extractor bar have in the ends thereof, vertical grooves 40, within which fit the arms of the extractor lever 14. The sides of the 65 tractor bar 39 are slightly converged at the

free end to resiliently grip the shell. This serves when the empty shell is drawn back to hold the same suspended in the track of the breech block 30 and the loaded shell 37 carried thereby, when the said breech block 70 is elevated by the closure of the lever 12 as hereinafter set forth.

The outward movement of the lever 12 is arrested by the pin 24, the lever 20 and link 21. When the lever 12 is brought to 75 rest as shown in Fig. 2 of the drawings, the pin 18 is disposed in line with the straight sides of the cams 16. It will be noted that the straight sides of the ends of the pin 18 are cut away to facilitate the movement of 80 the said ends on the straight sides of the blocks forming the cams 16.

When the pin 18 has been thus drawn to its downward limit, the shoulder 41 of the hammer 28 is engaged by the sear 42. The 85 sear 42 is retained in engagement with the hammer 28 and shoulder 41 thereof until the trigger 43 is moved to depress the latch end thereof to release the hammer 28. The hammer when released strikes the bolt 44, which 90 impinges upon the bolt of the firing pin bar 45, the pin 46 whereof is at the time in line with the percussion cap with which the shell is furnished. When the lever 12 is being closed, it swings on the pin 13 and the 95 ends 19 of the pin 18 are engaged with the straight front walls of the cams 16. The straight path formed by the inner surface of the loop 32 and the front wall of the cams 16, is substantially tangential to an arc 100 struck from the center of the pin 13. The result of this construction is that the movement of the lever 12 does not influence the lever 14 and parts connected therewith. These instrumentalities remain substantially 105 inert while the lever 12, link 21, lever 20, and breech block 30 are lifted. The breech block, because of the multiplied action resulting from the connection of the levers 20 and 12, is lifted rapidly. The rapidity of 110 movement of the breech block increases as it is lifted upward and as the pins 35 and 24 are drawn closer together.

When the pin 18 on the extension 33 of the lever 12 engages the straight surface of 115 the cam block 17, it will be found that the breech block and the loaded cartridge carried thereby have been lifted to a position where the empty shell held by the extractor 39 has been ejected from the grip of the 120 extractor 39, and it will also be found that the block 30 has moved to a position where the rim of the loaded shell has been disposed in the jaws 39' of the extractor. This is the position of the loaded shell and the 125 breech block while the lever 12 is moved so that the pin 18 is drawn backward along the path provided by the cams 16 and 17. During this movement of the lever 12, the extractor lever 14 is rocked on the pivot 15 130

and rapidly advances the extractor bar 39 and the shell carried thereby to the position shown in Fig. 1 of the drawings, the shell being placed in firing position within the 5 breech of the gun. When the pin 18 reaches the rear end of the straight wall of the cam 17, the extractor bar has completed its forward movement, and the cartridge is in the breech of the gun, but the breech block is 10 below the firing position.

By reference to Fig. 3 of the drawings, it will be seen that any upward movement of the block 30 during the period when the extractor bar is moving forward to deposit 15 the shell in the barrel of the gun is prevented by the toggle link 22 extending below the stop plates 49 of which there are two, one at either side of the spaced walls of the lever 12. When the lever 12 is depressed from the position shown in Fig. 1 20 to that shown in Fig. 2, the said lever swings on the pin 13, and the movements of the elevator 20 and the links 22 and 23 connected therewith are such as to place the nose of the 25 link 22 below the path of the stop plates 49. When the pin 18 reaches the bottom of the loop 32, it is carried forward and the lever 12 is swung to the position shown in Fig. 2 where the stop plates 49 extend into the path 30 of, for engaging, the ends of the link 22. It will be observed that when the lever 12 is being closed the pin 18 travels on the straight side of the cam 16, or in a path substantially tangential to an arc struck from the pin 13, 35 when in the advanced position shown in Fig. 2. The result of the construction is that when the ends 19 of the pin 18 engage the straight wall of the cam 17, the ends of the link 22 also engage the stop plates 49. The 40 mechanism controlling the elevator 20 and the breech block 30 is thus effectively arrested.

When the lever 12 is drawn back, the pin 18 following the path formed by the straight 45 sides of the cams 17, the plates 49 are retracted and removed from engagement with the ends of the link 22.

When the pin now passes out of engagement with the cam 17, it engages the curved 50 wall of the loop 32 of the hammer 28. This guides the pin in a path substantially concentric to the pin 13 in retracted position, as shown in Fig. 1 of the drawings. The further movement of the lever 12 does not affect 55 the lever 14, but operates to raise the lever 20 and the breech block 30 to the position where the bolt 45 and pin 46 are in the firing position.

The loaded cartridge is guided in its 60 movement from the position shown in Fig. 2, to the position where it is engaged by the extractor bar, by means of the cam-shaped inclined surfaces 47. The surfaces 47 converge and tend to force the loaded cartridge 65 backward to insure the placement of the rim

of the cartridge shell 37 in line with the jaws 39' of the extractor bar 39. The slight overhang 48 overcomes any tendency of the loaded cartridge to pass out of the receiver chamber or any tendency to disarrangement 70 owing to rapid movement of the breech block when lifting the cartridge to align with the barrel of the gun.

When constructed in accordance with the present invention, the gun is provided with 75 two magazines, each being adapted to hold five cartridges, such as are held in the usual cartridge clip. The magazines 50 and 51 are disposed at opposite sides of the gun and each magazine has a saddle 54 and end 80 sections 50" pivoted at 51", as shown in Fig. 4. Each magazine has a spring 52, for advancing the cartridges to the feeding position, or the door of the magazine. To this end, each spring has an overhanging hook 85 53, which rests above the cartridges. The door is a saddle 54 which rocks on a pin 55 and has its bearings in a gate 50' or 51' to transfer the cartridges successively from the chamber of the magazine to the saddle of the 90 breech block 30, as seen best in Fig. 7 of the drawings. The weight of the cartridges in the magazine overbalances the saddle 54 to cause the same to function in the manner described. The pressure of the spring 52 95 accelerates this action.

When the extractor lever 14 is rocked forward, the sides thereof strike and move the overhanging projection of the saddle 54 from the position shown at the right-hand of Fig. 100 7 to the cartridge-receiving position. As long as the lever 14 is in its forward position, the sides of the lever prevent the saddle 54 from rocking to feed the succeeding cartridge. When, however, the breech block 30 105 has been depressed to the position as shown in Fig. 7 and the extractor lever 14 rocked backward, the saddle is permitted to rock for the delivery of the next cartridge.

To lock the magazines jointly or selectively so that they will not feed, locking bars 56 and 57 are provided. These bars 56 and 57 have rack-toothed sections, the teeth whereof engage an intermediate pinion 58. The bars 56 and 57 have each a slide handle 115 59, by which the said bars are moved.

When the bars are evenly disposed, both magazines are locked, the ends of said bars extending in the path of, and preventing the rotation of the respective saddles 54. 120 This may be seen at one side of Fig. 7. When, however, it is desired to feed the shells from the magazine at one side of the gun, either the bar 56 or 57, as the case may be, is drawn back, causing the said bar to be 125 inserted into the path of the saddle 54 with which it is associated, while through the medium of the pinion 58, the bar at the opposite side is inserted in the path of the saddle 54 with which it is associated. Thus it will 130

be seen that the feed of shells from the magazines may be selected or the firing from both magazines may be discontinued to permit, if desired, the introduction by hand of 5 a single shell upon the breech block at the top thereof.

After the magazine has been emptied and the last shell in the barrel has been fired, the hand lever is rocked to the open position to extract the shell from the barrel. 10

The shell is now depressed to release it from the extractor by any means, preferably by an empty shell, to a position on the upper face of the breech block, and if the 15 lever 12 is moved to the closed position with the riding pin 18 traveling through the rear passage of the cam 16, the breech block 30 is moved vertically to eject the shell after the extractor has been moved to forward 20 position, it being understood that the shell passes between the parallel arms of said ejector.

The lower portions of the magazines 50 and 51 are closed normally by hinged gates 25 50' and 51', which can be swung outwardly to permit the cartridges to be forced upwardly into the magazines against the action of the springs 52, the open position of these gates being shown in dotted lines in Fig. 6. 30

Claims.

1. The combination with a breech loading rifle having a breech block, an extractor, and a side feeding magazine; of a gun action 35 comprising an extractor lever pivoted on the gun structure and having a short pendent end, a hand lever pivotally connected with said extractor lever at the extremity of said short end, and means for guiding said hand lever for rocking said extractor lever.

2. The combination with a breech loading rifle having a breech block, an extractor, and a side feeding magazine; of a gun action 45 comprising an extractor lever pivoted on the gun structure and having a short pendent end, a hand lever pivotally connected with said extractor lever at the extremity of said short end, and means for guiding said hand 50 lever for rocking said extractor lever, said means embodying a plurality of cam blocks, said blocks having guiding surfaces for engagement with said hand lever.

3. The combination with a breech loading 55 rifle having a breech block, an extractor, and a side feeding magazine; of a gun action comprising an extractor lever pivoted on the gun structure and having a short pendent end, a hand lever pivotally connected 60 with said extractor lever at the extremity of said short end, and means for guiding said hand lever for rocking said extractor lever, said means embodying a plurality of pins mounted on said hand lever and extended from the side thereof, and a plu-

rality of cam blocks for guiding said pins for moving the hand lever lengthwise of the gun.

4. The combination with a breech loading rifle having a breech block, an extractor, and a side feeding magazine; of a gun action comprising an extractor lever pivoted on the gun structure and having a short pendent end, a hand lever pivotally connected with said extractor lever at the extremity of said 70 short end, and means for guiding said hand lever for rocking said extractor lever, said means embodying a pin laterally extended from said hand lever, a plurality of cam blocks forming guideways for said pin, said cam blocks being shaped to provide a plurality of paths for said pin for rocking said extractor lever lengthwise of said gun. 75

5. The combination with a breech loading rifle having a breech block, an extractor, and a side feeding magazine; of a gun action comprising an extractor lever pivotally mounted on the gun structure and having a short pendent end, a hand lever pivotally supported at the extremity of said pendent end, means for guiding the movement of the free end of said hand lever for moving the end thereof connected with said extractor lever reciprocatively in a path parallel with the length of the gun; an elevator lever 85 for said breech block, said lever being pivotally and permanently connected with said block, the free end of said lever having a roving pivot connection with the gun structure, a link connecting said elevator lever and hand lever, stopping means mounted on said elevator lever intermediate the pivot ends thereof for engaging the hand lever to arrest the upward movement of said lever and breech block connected therewith; and means for moving said hand lever out of engagement with said stopping means for permitting the upward movement of said elevator lever and breech block connected therewith. 90

6. The combination with a breech loading rifle having a breech block, an extractor, and a side feeding magazine; of a gun action comprising a pivotally mounted hand lever, an elevator lever for raising and lowering said breech block, movement-multiplying connections between said hand lever and elevator lever for accelerating the movement of said elevator lever during the first periods of the movement of said hand lever, stopping means for arresting the action of said elevator lever when the breech block has arrived at the loading position, means for withdrawing the hand lever from engagement with said stopping means, the extractor moving in correspondence with said hand lever for moving the shell carried by the breech block into the plane of the barrel, and means for continuing the action of said hand lever and breech block elevator lever 105 110 115 120 125 130

- connected therewith to the firing position of said breech block. 65
7. The combination with a breech loading rifle having a breech block, an extractor, and a side feeding magazine; of a gun action comprising a hand lever adapted for movement pivotally and reciprocatively for lowering and for raising the breech block, respectively and successively. 70
- 10 8. The combination with a breech loading rifle having a breech block, an extractor, and a side feeding magazine; of a gun action comprising an extractor lever pivotally mounted on the gun structure and slidably connected with said extractor, an elevator lever pivotally connected with said breech block and slidably connected with said gun structure, and a hand lever pivotally connected with and supported by said extractor lever and elevator lever for moving said levers successively to function independently. 75
- 25 9. The combination with a breech loading rifle having a breech block, an extractor, and a side feeding magazine; of a gun action comprising an extractor lever pivotally mounted on the gun structure and slidably connected with said extractor, an elevator lever pivotally connected with said breech block and slidably connected with said gun structure, a hand lever pivotally connected with and supported by said extractor lever and elevator lever for moving said levers successively to function independently, and 80 means for dividing the movement of said elevator lever for disposing the breech block connected therewith in the loading and firing positions thereof successively. 85
- 30 10. The combination with a breech loading rifle having a breech block, an extractor, and a side feeding magazine; of a gun action comprising an elevator lever for said breech block; a plurality of magazines, disposed on opposite sides of the gun structure and each having a rocking gate; and means for selectively locking said gates. 90
- 35 11. The combination with a breech loading rifle having a breech block, an extractor, and a side feeding magazine; of a gun action comprising an elevator lever for said breech block; a plurality of magazines, disposed at opposite sides of the gun structure and each having a rocking gate; and means for selectively locking and releasing said gates. 95
- 40 12. The combination with a breech loading rifle having a breech block, an extractor, and a side feeding magazine; of a gun action comprising an elevator lever for said breech block, a plurality of magazines, disposed at opposite sides of the gun structure and each having a rocking gate, and means for selectively locking and releasing said gates, said means embodying a plurality of 100
- 45 rack bars slidably arranged with relation to said gates for interposition in the path of movement thereof. 105
- 50 13. A gun action comprising a bifurcated extractor, the ends whereof are adapted for engagement with the rim of a cartridge shell; a bifurcated extractor lever slidably connected with said extractor and pivotally mounted on the gun structure for providing a short pendent end extension; a breech block having an elevator saddle formed 110 therein; a firing pin and bolt thereof slidably mounted in said breech block and slidably connected with the gun structure; a firing hammer pivotally mounted and adapted to move said firing pin and bolt, said hammer having a guide loop formed in the body thereof; and a hand lever pivotally connected with the extended end of said extractor lever, with the said elevator lever, and with said hammer, said hand lever being suspended by said two first-mentioned levers and said hammer for rocking said levers and for cocking said hammer in mutually timed relation, the guide loop in said hammer controlling the movement of said hand lever to swing the same lengthwise of the gun. 115
- 55 14. A gun action comprising a bifurcated extractor, the ends whereof are adapted for engagement with the rim of a cartridge shell; a bifurcated extractor lever slidably connected with said extractor and pivotally mounted on the gun structure for providing a short pendent end extension; a breech block having an elevator saddle formed 120 therein; a firing pin and bolt thereof slidably mounted in said breech block; an elevator lever pivotally connected with said breech block and slidably connected with the gun structure; a firing hammer pivotally mounted in said gun structure and adapted to move said firing pin and bolt, said hammer having a guide loop formed in the body thereof, a hand lever pivotally connected with the extended end of said extractor lever, with the said elevator lever, and with said hammer, said hand lever being suspended by said two first-mentioned levers and said hammer for rocking said levers and for cocking said hammer in mutually timed relation, the guide loop in said hammer controlling 125 the movement of said hand lever to swing the same lengthwise of the gun; and means connected with said elevator lever for engaging said hand lever to arrest the upward movement of the end of said elevator lever intermediate the full movement of said elevator lever for placing the breech block connected with said elevator lever in alined position, said engagement being released by the movement of said hand lever in correspondence with the guide loop on said hammer. 130

LUIS B. HOCHSTEIN,
